UNITED STATES PATENT OFFICE

ALEXANDER RISPEL AND LOUIS C. LIEDTKE, OF CHICAGO, ILLINOIS

HAM BOILER

Application filed October 2, 1926. Serial No. 139,040.

Our invention relates to an improved ham boiler, embodying, among other features:

First, immunity from jolts and jars both as to accidental disconnection of the parts and 5 as to shifting of the cover.

Second, suitability for being tensioned either by hand or in a power press.

Third, protection against breakage due to extreme pressures applied with a power 10 press, or in any other way.

Fourth, a maximum leveling effect during cooking.

Further objects and advantages of the invention will become apparent as the description 15 proceeds.

In the accompanying drawings:

Figure 1 is a central, longitudinal section, partly in elevation, of one embodiment of the invention;

20 Figure 2 is a section on line 2—2 of Figure 1; and

Figure 3 is a section on line 3—3 of Figure 1.

In the embodiment of the invention selected for illustration the container 10 receives a ham, or other material to be cooked, while under resilient pressure, which pressure is applied by means of the cover 12 telescoping inside the receptacle. For applying 25 the resilient pressure we employ coil springs 14 located at extreme ends of the cover on the longitudinal center line of the boiler. The lower ends of the springs are preferably held against accidental displacement by bosses 16 30 on the cover.

At the top of each spring is an abutment member 18. The top of the spring may be held against displacement with respect to the abutment 18 in the same way as the lower end 40 of the spring, but we prefer to employ a stud 20 extending down part way inside the spring. When such a stud is employed it is preferably made square to reduce the area of contact between the stud and the coils of the 45 spring and minimize friction.

The means for holding down the abutments 18 comprises a tension member, or hold-down 22 for each abutment. Each hold-down comprises a relatively straight portion 24 provided with a series of rack teeth 26 adapted to

hook over the tooth 28 on the edge of the receptacle and prevent upward movement of the tension member; and a curved portion 30 extending in over the end of the cover 12 almost, but not quite, to the center line of the spring 14. The tension member has a bifurcated end pivoted on a pintle 32 passing through the abutment 18.

To guide the parts and hold them in satisfactory alignment, without interfering with the freedom of motion necessary to permit the contents of the receptacle to expand and contract during treatment, we provide a vertical guide 34 close beside each spring. The guide 34 preferably has an H section rather well filled in and slides in a vertical guide-way 36. The side walls of this guide-way are cut away at 38, partly to save metal and facilitate cleaning and partly to afford a slot for receiving a limit stop 40, illustrated as a simple machine screw passing through the lower end of the guide and projecting into the slot.

To brace the structure and increase its rigidity, we prefer to connect the guide-ways 36 at opposite ends of the boiler by a beam or reach 42, thereby constituting both guide-ways and the reach a rigid bridge materially reinforcing the cover 12. The feet of the guide-ways are more or less enlarged, as at 44, to engage the surface of the cover over a substantial area, and the whole is fastened to the cover in any suitable way, as by machine screws 46.

In use, the ham, or other article to be cooked, is placed in the receptacle and the cover set on top of it. It is now necessary to push the abutments 18 down and compress the springs while the tension members ride over the teeth 28 and prevent return movement. In large installations this is done in a power press which moves a flat plate or beam down from above to engage both abutments simultaneously. When such a press is used an ignorant workman may, and often does, apply the pressure much more vigorously than is necessary or desirable. As the contents of the receptacle is usually pushing harder against the middle of the cover than the ends at first, there is

danger of breaking the cover by buckling it up in the middle when the device is thus improperly handled. It will be noted from the drawings that the distance A in Figure 5 down to the reach 42 is equal to the clearance between the guide 34 and the cover and also equal to the clearance between the studs 20 and the bosses 16. Thus, the abnormal and improper load will be transmitted to the 10 cover, not only at points corresponding with the bosses 16 or with the ends of the guides, but also over much larger areas spaced much nearer the center of the cover, to wit, the feet 44 of the guide-ways.

15 On the other hand, in a smaller establishment where no power press is available, the complete independence of the two abutments 18 makes it relatively easy for a workman to place his foot first on one abutment and 20 then on the other and get both springs properly compressed. The strength of these springs in a unit of ordinary size is such that a man of ordinary weight could not conveniently compress both springs at the same 25 time by means of his weight.

The location of the springs 14 at the extreme ends of the cover results in a maximum leveling effect. If the contents of the container tends to hold the cover with one end 30 tipped up, say one-half inch higher than the other, the excess in the spring tension at the high end over that at the low end will be greater and its effective lever arm longer than with the springs located a less distance 35 from the center.

Neither the abutments 18 nor the tension members 30 are rigid with the cover 12, there being considerable looseness to permit the guides 34 to move freely without binding. 40 An accidental blow from one end, as by throwing another container up against the end of a container already stacked in the boiling vat, will ordinarily strike the straight portion 24 of the tension member and have 45 no appreciable effect other than to push it against the tooth 28. However, if the impact should come at a slight angle from above it would strike the curved portion 40 intermediate the pivot 32 and the tooth 28. The 50 impact would thus be distributed between the body of the receptacle and the cover. Where, as in prior devices, parts rigid with the cover, or having relatively little play with respect thereto, project out substantially into the vertical plane of the straight portions 55 24, such impacts will always be delivered to the cover and shift the cover to and fro in the receptacle. If they happen to be at all violent, this shift may readily unhook the 60 tension member at the remote end of the receptacle. These objections are eliminated by the construction herein above set forth.

Without further elaboration, the foregoing will so fully explain the gist of our invention that others may, by applying cur-

rent knowledge, readily adapt the same for use under various conditions of service without eliminating certain features which may properly be said to constitute the essential items of novelty involved, which items are 70 intended to be defined and secured to us by the following claims.

We claim:

1. A ham boiler comprising a receptacle, a cover telescoping inside said receptacle, springs near the ends of said cover for pressing down on said cover, abutments riding on the upper ends of said springs to compress said springs, hold-downs pivoted on said abutments, pawl and rack means acting between said hold-downs and receptacle to prevent upward movement of said hold-downs, a vertically slideable guide for each spring abutment, said guides being offset beside said springs on the center line of the 85 boiler nearer the center than said springs, a spring guiding stud on each abutment, projecting down inside the spring to keep said spring in alignment, and a bridge rigid with said cover, said bridge comprising a central 90 reach, vertical end portions slidably receiving said guides, and enlarged feet at the bottoms of said end portions, said feet resting on the cover, and said reach extending up to such a level that a straight implement 95 employed to press down said abutment will strike said reach at the same time that said studs and said guides engage said cover, and a stop for each guide preventing complete separation of said guide and cover. 100

2. A ham boiler comprising a receptacle, a cover telescoping inside said receptacle, springs for pressing down on said cover, abutments riding on the upper ends of said springs to compress said springs, hold-downs pivoted on said abutments, pawl and rack means acting between said hold-downs and receptacle to prevent upward movement of said hold-downs, a guide for each spring abutment, and a bridge rigid with said cover, said bridge comprising a central reach and vertical end portions slidably receiving said guides, said reach extending up to such a level that a straight implement employed to press down said abutments will strike said reach at the same time that said guides engage said cover. 110

3. A ham boiler comprising a receptacle, a cover telescoping inside said receptacle, springs riding on said cover at the ends thereof, abutments riding on said springs, and connections for holding said abutments in place comprising offset guides rigid with said abutments and vertically slideable with respect to said cover, offset tension members pivoted on said abutments, and tooth and rack means on said tension members and receptacle for holding said tension members down, said tension members and guides being offset substantially equally on opposite 120 125

sides of said springs along the center line of the boiler.

4. A ham boiler comprising a receptacle, a cover telescoping inside said receptacle, 5 springs riding on said cover, abutments riding on said springs, and connections for holding said abutments in place comprising offset guides rigid with said abutments and vertically slidable with respect to said cover, 10 and offset tension members pivoted on said abutments, and tooth and rack means on said tension members and receptacle for holding said tension members down, said tension members and guides being offset on opposite 15 sides of said springs.

5. A ham boiler comprising a receptacle, a cover telescoping inside said receptacle, springs riding on said cover, abutments riding on said springs, and connections for 20 holding said abutments in place comprising abutment guides, offset tension members, pivoted on said abutments, and tooth and rack means on said tension members and receptacle for holding said tension members 25 down, said tension members and guides being offset on opposite sides of said springs.

6. A ham boiler comprising a receptacle, a cover telescopically movable toward and away from said receptacle to compress material between itself and the receptacle, 30 resilient means symmetrically placed near the ends of said cover for pressing down on said receptacle, tensioning means, and means for limiting the tension, said limiting means 35 establishing a direct thrust connection to the cover over two distributed symmetrically placed areas thereof extending nearer to the center than said resilient means.

7. A ham boiler comprising a receptacle, 40 a cover telescoping inside said receptacle, a centrally located reach rigidly mounted on and bracing said cover, and resilient means located at the ends of said reach and leaving the space above the same free and unobstructed, for connecting said receptacle and cover 45 and pressing said cover down.

In witness whereof, we hereunto subscribe our names this 28th day of September, 1926.

ALEXANDER RISPEL.
LOUIS C. LIEDTKE.
